US0D1075283S

(12) **United States Design Patent** (10) **Patent No.:** **US D1,075,283 S**
(45) **Date of Patent:** **** May 20, 2025**

(54) **KEY HOLDER**

(71) Applicant: **Hefei Youlifa Trade Co., LTD**, Hefei (CN)

(72) Inventor: **Guangqi Xu**, Hefei (CN)

(73) Assignee: **Hefei Youlifa Trade Co., LTD**, Hefei (CN)

(**) Term: **15 Years**

(21) Appl. No.: **29/880,150**

(22) Filed: **Jul. 18, 2023**

(51) LOC (15) Cl. **03-01**

(52) U.S. Cl.

USPC **D3/207**

(58) **Field of Classification Search**

USPC D3/207, 208, 209, 210, 211, 215

CPC Y10T 24/1379; Y10T 70/8676

See application file for complete search history.

(57) **CLAIM**

The ornamental design for a key holder, as shown and described.

DESCRIPTION

FIG. 1 is a top perspective view of a key holder, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1. The dash-dot-dash broken lines encircling the enlarged views are for annotative purposes only and form no part of the claim thereof.

1 Claim, 9 Drawing Sheets
